UNITED STATES PATENT OFFICE.

JOHN C. WOODSOME, OF NEWTON, MASSACHUSETTS.

DOUBLE-WALL VENTURI STEAM FITTING.

Application filed January 9, 1926. Serial No. 80,230.

This invention relates to a double wall Venturi steam fitting, more particularly adapted for use in connection with a steam circulating system for paper machine driers.

In my copending application Serial No. 2,868, filed January 16, 1925, I explained the construction, use and advantages of a simple Venturi type of steam fitting as applied to paper machines. My present invention is an improvement over my former device in that my Venturi fitting is now provided with removable inner members, thus making replacement more easily accomplished whether for the purpose of installing a new member or a member of different size. Furthermore, in my present circulating system I provide two Venturi types of fittings, one in the steam inlet line to act as a circulator and one in the exhaust line from the driers to act as a separator. In this way I obtain a more rapid and positive circulation even than heretofore.

It is therefore an object of this invention to provide an improved double wall Venturi circulator especially adapted to effect a rapid and efficient circulation of steam through driers and to afford positive suction means for the removal through a Venturi separator of condensate, air and non-condensable gases from the driers and for the separation of said condensate, air and non-condensable gases from the steam.

It is a further object of this invention to provide a steam circulating system for driers that will materially increase the thermal efficiency of the driers and which will therefore result in substantial economies in the drying process.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary end view of a paper machine drier having connected therewith a steam circulating system employing my improved double wall Venturi circulator and separator, with parts in section.

Figure 2 is a side elevational view of the same, with parts in section.

Figure 3 is a longitudinal sectional view showing the construction of my double wall Venturi circulator.

Figure 4 is a longitudinal sectional view showing the construction of my double wall Venturi separator.

As shown on the drawings:

The reference numeral 1 refers to a drum drier of the usual type found in paper making machines. The customary method of heating such a drum is by introducing live steam thereinto through a hollow journal, the drum itself acting as a condenser to condense a portion of the steam. The condensed steam forms a film on the inside of the drum and will, if not removed, form a very effective insulating medium which acts to cut down the rate of transfer of heat through the drum shell to the paper in contact therewith. Accordingly it is very important to remove the condensate as quickly as formed, or otherwise the thermal efficiency of the drier will be greatly reduced, with consequent poor economics and with deleterious effect on the quality of paper made. The methods in common use now for removing the condensed steam from the drier are either the bucket or the siphon type system. My Venturi circulator and separator may be employed with either system, but is here shown in connection with a condensate removal system of the siphon type.

The drum 1 is provided at its rear end with a hollow journal 2 supported in a suitable bearing 3 which in turn is mounted on a structural support 4. A driving gear 5 is secured to the journal 2 on the other side of the bearing 3 from the drying drum. A self-adjusting oil-less steam fitting 6 is provided for the end of the journal 2 which extends beyond the gear 5. A siphon pipe 7 extends from a point near the bottom of the drum 1 through the entire length of the hollow journal 2 and through the elbow of the steam fitting 6. The steam fitting 6, which is supported by an upright supporting member 6^a, is connected by a steam inlet pipe 8 to a steam supply header 9. In this steam inlet pipe 8 I connect at any suitable point a Venturi circulator 10 of my improved double wall type. Said circulator 10 (Figure 3) comprises an outer casing 11 having flanged ends 12 and 13 adapted to be secured respectively to a flanged ring 14 on the pipe 8 and to a flanged conical section 15 forming an extension to the diffuser member of the circulator. Said section 15 is provided at its other end with an internally threaded

portion 16 into which is threaded a nipple 17, which forms a part of the pipe 8. Said outer casing 11 may be cylindrical or may be slightly constricted as shown, and is provided at its constricted portion with a side opening 18 threaded to receive a suction pipe 19.

The Venturi circulator proper comprises a pair of conical shaped members 20 and 21, which I will call the diffuser and throat, respectively. The diffuser 20 is a relatively long member, slightly tapered to form a constricted opening or orifice 22, beyond which said member is flared outwardly as at 23 for a short distance. An annular flange 24 on the large end of the diffuser 20 is adapted to fit into a corresponding recess in the flange 13 and to be clamped therein between said flange 13 and the flange of the diffuser extension 15. Abutting lugs 25 and 26 are formed on the inside of the casing 11 and on the outside of the diffuser 20 to properly position the diffuser 20 within said casing. The throat 21 is similar in construction to the diffuser 20 but is relatively shorter and of larger diameter at its big end and has a smaller constricted portion 31. It is suitably held in place by means of a flange 27 adapted to be clamped between the abutting flanged ends 12 and 14 and by means of positioning lugs 28 and 29. Said diffuser 20 and throat 21 are so positioned as to provide a gap 30 between their respective adjacent ends, said gap being centrally located of the opening 18 and in communication therewith.

It follows from the well known principles of a venturi that at the constricted portion 31 of the throat 21 the velocity of the steam passing through will be greater than that of the steam in the pipe 8. The increased velocity of the steam as it issues from the throat 21 will therefore cause a certain amount of suction through the gap 30 and a reduced pressure in the suction line 19. Said suction line 19, however, is connected with a separator 32 in a steam exhaust line 33 forming a continuation of the siphon 7. The separator 32 (Figure 4) is similar in construction to that of the circulator 10, the main difference being in the dimensions of the Venturi parts 34 and 35. Said parts 34 and 35 are removable, as are the diffuser 20 and throat 21 of the Venturi circulator 10, and are similarly spaced to form a gap 36. On one side of said gap 36 and slightly above the same there is provided an air valve 37. The suction pipe 19 enters the separator on the other side of the air gap 36 and on a level therewith. A continuation of the exhaust or drain pipe 33 leads into a return header 38.

The operation of my steam circulating system is substantially as follows. Steam under pressure enters the drier 1 from the supply header 9 through the pipe 8 and the

Venturi circulator 10. In passing through the constricted orifice 31 of the throat 21, the velocity of the steam is greatly increased, with the result that in passing across the gap 30 the steam creates sufficient vacuum in the suction pipe 19, separator 32 and siphon 7 to effect a rapid circulation through said pipe, separator and siphon. The condensed steam, air and non-condensable gases, together with a certain amount of uncondensed steam from the drier drum are all drawn through the siphon pipe 7 into the Venturi separator 32, where the air and non-condensable gases are separated out through the air valve 37. The condensate, because of its greater momentum, passes straight through the Venturi members 34 and 35 into the drain pipe 33. Whatever uncondensed steam is sucked over into the Venturi separator 32, is drawn off through the suction pipe 19 by the suction action created at the orifice 31 of the throat 21 and is recirculated through the drier.

It will thus be apparent that my Venturi circulator effects a positive circulation of the steam through the drier and that my Venturi separator provides for the separation of the air, non-condensable gases and water of condensation from the live steam. The advantage of my system is evidenced by actual tests made with and without my Venturi circulator and separator, wherein an increase in the efficiency of the drier of over 20% was obtained by using the same.

One important advantage of the double wall construction in the Venturi circulator and separator is that the size of the inner Venturi members may be varied, using the same size outer casing. Furthermore, the inner members being removable, can be replaced when worn or corroded. As there are no moving parts, the amount of wear and tear is reduced to a minimum and is considerably less than would be the case where mechanical pumps of the piston or rotary type are used to effect circulation of steam through the drier. As is obvious, the size and type of throat fitted to the separator will influence to a great extent the efficiency obtained from the drier. In general, it has been found advisable to use separators with smaller throats on the driers at the dry end, gradually increasing the size of the throats on the separators toward the wet end of the paper machine.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A steam circulating system for driers, comprising a steam inlet pipe into a drier,

a Venturi type of fitting connected in said pipe, an exhaust pipe from said drier, a Venturi type of fitting in said exhaust pipe and a connection between the constricted portions of said fittings.

2. The combination with a paper making machine drier drum, of a steam supply pipe, a steam inlet pipe connecting the steam supply pipe with the interior of the drier drum, a drain line leading from within the drier drum, a Venturi circulator in the steam inlet pipe and a Venturi separator in the drain line connected to said circulator.

3. The combination with a paper making machine drier drum, of a steam supply pipe, a steam inlet pipe connecting said steam supply tank to the interior of the drier drum, a drain line leading from within the drier drum, Venturi type fittings in said

inlet and drain lines, each of said fittings having a side opening, and a pipe secured in said openings for recirculating uncondensed steam.

4. The combination with a paper making machine drier drum, of a steam supply pipe, a steam inlet pipe connecting said steam supply tank to the interior of the drier drum, a drain line leading from within the drier drum, Venturi type fittings in said inlet and drain lines, each of said fittings having a side opening, a pipe secured in said openings for recirculating uncondensed steam, and an air valve associated with the Venturi type fitting in said drain line to separate out air and non-condensable gases.

In testimony whereof I have hereunto subscribed my name.

JOHN O. WOODSOME.
